MASSAGE DEVICE

James L. Younghusband, Chicago, Ill.

Application July 31, 1937, Serial No. 156,775

8 Claims. (Cl. 128—63)

My invention relates to a device for applying massage and vibration to the body of the user reclining thereon.

Among the objects of my invention is to create a device having a plurality of body supporting members, some of which move in opposite directions to other members so as to impart a different pull with each member to the body of the user. To provide a device in which some of the body supporting members move while others are stationary; to supply a device in which the body supporting members have a covering, portions of which are moved by the said underlying members, and such other objects, advantages and capabilities as will later more fully appear and which are inherently possessed by my invention.

Referring to the drawing Fig. 1 is a perspective view and Fig. 2 a partial plan view of one embodiment of my couch; Fig. 3 is a detail view of the strap arrangement and Fig. 4 is a perspective view partly broken away of another embodiment of my invention; Fig. 5 illustrates the stationary members; Fig. 6 is a detail plan view and Fig. 7 a detail side view of my gear mechanism.

While I have shown in the accompanying drawings preferred embodiments of my invention, yet I wish it understood that the same are susceptible of modification and change without departing from the spirit of my invention.

Referring to the embodiment shown in Figs. 1, 2 and 3 to illustrate my invention, it comprises a frame 10 with legs 11. A pair of spaced lengthwise extending members or rods 12 are rotatably attached to the frame 10 by bearings 13. A plurality of straps 14 and 15 extend transversely between the rods 12. Straps 14 alternate with straps 15. Straps 14 extend over the top portion of the rod on one side and under the bottom portion of the rod on the other side. Straps 15 correspondingly extend under the bottom portion of the rod on one side and over the top portion of the rod on the other side. Straps 14 and 15 are attached to the rods 12 by suitable clamping means such as shown at 22.

In use the user reclines on the straps 14 and 15. Motive power from a motor 20 is then applied through gear 30 to vertical rod 26 which through gear box 25 having positive and reverse gears causes rotational oscillation of horizontal rods 27, which motion is transferred to rods 12 through worm gear mechanism 21 causing them to rotate on bearings 13 in opposite directions. This causes straps 14 to move back and forth within limits, and straps 15 to move back and forth within limits and in opposite directions to

the movements of straps 14 thereby imparting a simultaneous different pull from each strap to that part of the body contacted thereby. This provides a massage. In addition the skin of the body of the user is caused to move by the movement of the straps and friction is created. The massage, friction and vibration thus set up acts as a reducing means even while the user is in a reclining position.

I may provide a pair of reinforcing members 16 to hold the body within the central portion of the couch and attach to said straps 14 and 15 to protect the ends of the straps from too great a pressure adjacent their connection with the rods 12.

I may also provide my straps 14 and 15 with ribs 18 and/or holes 19 to aid in the massage and friction.

Another embodiment of my invention shown in Fig. 4 provides for a covering 17 of soft rubber sheeting or other resilient material for covering the straps 14 and 15. Upon movement of the straps 14 and 15 portions of the covering 17 will move in opposite directions causing massage and movement of the body, friction and vibration for reducing the weight of the user.

Variations of the embodiment of my invention shown in Figs. 1, 2 and 3, without departing from the spirit of my invention, contemplate instead of having one strap 14 and the next strap 15, to have two or any plurality of straps 14 and two or any plurality of straps 15, or one strap 14 or 15 followed by two or more straps 15 or 14 respectively. Such variations may of course add the covering 17 shown in Fig. 4.

My invention also includes the embodiment of a plurality of stationary straps 23 attached to the lengthwise extending portions 24 of the frame 10. These straps 23 may be scattered among movable straps 14 and 15 in any proportion of the three straps 23, 14 and 15. Straps 23 may be used only with straps 14 or 15 so that the movable straps may all move back and forth in the same direction at the same time. The covering 17 may also be added to any of these forms of my invention.

While I have shown the body supporting members 14, 15 and/or 23 in a transverse position and rotating rods 12 as lengthwise, yet their position may be reversed so that the body supporting members may be in a lengthwise position and the rotating rods at the ends thereof in a transverse position thereto.

Having thus described my invention I claim:

1. A reducing couch comprising a frame, a

55

pair of lengthwise extending members rotatably attached to said frame, a plurality of members extending transversely between and attached to said lengthwise extending members for holding the body of a user in reclining position, a plurality of transverse members extending over the top of the lengthwise extending member on one side and under the bottom of the lengthwise extending member on the opposite side and another plurality of transverse extending members extending under the bottom of the lengthwise extending member on one side and over the top of the lengthwise extending member on the opposite side, means for rotating said lengthwise extending members for simultaneously moving said first named plurality of transverse extending members in opposite directions to said another plurality of transverse extending members so that a different pull is imparted to the body of the user by each transverse extending member to thereby increase the massage.

2. A reducing couch comprising a frame, a pair of lengthwise extending members rotatably attached to said frame, a plurality of members extending transversely between and attached to said lengthwise extending members for holding the body of a user in reclining position, alternate transverse members extending over the top of the lengthwise extending member on one side and under the bottom of the lengthwise extending member on the opposite side and intermediate transverse extending members extending under the bottom of the lengthwise extending member on one side and over the top of the lengthwise extending member on the opposite side, means for rotating said lengthwise extending members for simultaneously moving alternate transverse extending members in opposite directions to intermediate transverse extending members so that a different pull is imparted to the body of the user by each transverse extending member to thereby increase the massage.

3. A reducing couch comprising a frame, a pair of spaced rods rotatably attached to opposite portions of said frame, a plurality of members extending between and attached to said rods for holding the body of a user in reclining position, a plurality of members extending over the top of the rod on one side and under the bottom of the rod on the opposite side and another plurality of members extending under the bottom of the rod on one side and over the top of the rod on the opposite side, means for rotating said rods for simultaneously moving said first named plurality of said members in opposite directions to said another plurality of members so that a different pull is imparted to the body of the user by each member to thereby increase the massage.

4. A reducing couch comprising a frame, a pair of spaced rods rotatably attached to opposite portions of said frame, a plurality of members extending between opposite portions of said frame and immovably attached thereto, a plurality of members extending between and attached to said rods, all of said members adapted to hold the body of a user in reclining position, a plurality of said members extending over the top of the rod on one side and under the bottom of the rod on the opposite side, and another plurality of members extending under the bottom of the rod on one side and over the top of the rod on the opposite side, means for rotating said rods for simultaneously moving said first named plurality of members in opposite directions to said another plurality of members so that a different pull is imparted to the body by each member to thereby increase the massage.

5. A massage device comprising a frame, a pair of movable members attached to said frame, a plurality of members attached to said movable members for holding the body of a user in reclining position, and means for oscillating said movable members for moving some of said body holding members in opposite directions to other of said body holding members so that a different pull is imparted to the body of the user by each of said body holding members to thereby increase the massage.

6. A massage device comprising a frame, a pair of spaced members rotatably attached to said frame, a plurality of members extending between and attached to said spaced members for holding the body of a user in reclining position, and means for rotationally oscillating said spaced members for moving some of said body holding members in opposite directions to other of said body holding members so that a different pull is imparted to the body of the user by each of said body holding members to thereby increase the massage.

7. A massaging apparatus comprising a bed-like frame, a plurality of massaging elements supported therein for reciprocable movement with respect thereto, means for reciprocably moving a number of said elements with respect to said frame, and means for reciprocably and simultaneously moving the balance of said elements with respect to said frame in a direction opposite to the movement of said first mentioned number of elements.

8. A massaging apparatus including a frame, a plurality of crosswise elements movably supported therein and adapted to support the human body, and means for reciprocating various ones of said elements in different directions at different times.

JAMES L. YOUNGHUSBAND.
